MILTON L. ALMQUIST, OF BROOKLYN, NEW YORK, ASSIGNOR TO AMERICAN TELEPHONE AND TELEGRAPH COMPANY, A CORPORATION OF NEW YORK.

RADIO SIGNALING SYSTEM EMPLOYING MACHINE-SWITCHING DIAL.

Application filed May 27, 1924. Serial No. 716,208.

This invention relates to signaling circuits and more particularly to arrangements for transmitting selective signals over circuits employing carrier frequencies such, for example, as multiplex carrier systems or radio signaling systems.

In systems employing high frequency currents as carriers of signals and particularly in the case of radio signaling systems, it is desirable to provide selective arrangements for transmitting ringing or other supervisory signals by means of code combinations. This is desirable not only to insure that the proper receiving stations will be selected and signaled, but also to prevent false operation of a signal at any stations by means of transient disturbances.

In accordance with the invention it is proposed to provide a signaling system of the type above described which will utilize as the code forming mechanism at the transmitting station the ordinary dial used in machine switching and which will preferably employ at the receiving station a selective switch of the type employed in machine switching. The invention also comprises, among other things, the provision of a special selective circuit arrangement whereby the switch may be successively operated in response to successive groups of code impulses to establish the final signaling circuit at the receiving station. By this arrangement it is possible to assign each receiving station a number and by simply dialing the code number, the desired receiving station will have its selective apparatus so operated as to activate the signal at that station, while the other stations having different numbers will not have their signaling apparatus operated.

The invention may now be more fully understood from the following description when read in connection with the accompanying drawing, Figure 1 of which illustrates schematically the arrangement of the apparatus embodying the invention as applied to a transmitting and a receiving station of a radio signaling system, and Fig. 2 of which illustrates the circuit details of the selecting mechanism employed at the receiving station, and Figs. 2^a and 2^b of which show details of the switch mechanism.

Referring to Fig. 1, TL designates an ordinary telephone transmission line which

is connected over the contacts of a relay 21 to radio transmitting apparatus, conventionally indicated at T. This apparatus may be of any type well known in the art whereby telephonic waves may be impressed upon the radio frequencies and transmitted from an antenna such as TA. For example, the apparatus may be of the type shown in United States patent to H. A. Affel, No. 1,472,822, of November 6, 1923. In order to transmit a ringing signal through the radio transmitter, a dial D is provided, this dial being of the type commonly employed in connection with machine switching systems. A source of ringing current 20 is provided, having a frequency, for example, of 135 cycles, and the contacts of the relay 21 are so arranged that whenever the relay is de-energized the radio transmitter is disconnected from the line TL and the ringing current connected to the transmitter for modulating the radio frequency in any well known manner. The circuit of the relay 21 is normally closed through contacts of the dial D so that when the dial is operated the circuit of the relay 21 is successively opened a number of times corresponding to the particular digit dialed. This permits of the transmission of groups of 135 cycle oscillations corresponding in number to the number of pulses transmitted by the dial. The off normal contact of the dial is arranged to connect ground to the starting lead of the ringing current source to set the generator of said source into operation in a well known manner. See, for example, United States patent to C. S. Demarest, No. 1,317,155, of September 30, 1919.

The receiving apparatus comprises a receiving antenna RA with which is associated a radio receiving mechanism conventionally illustrated at R. This mechanism may be of any well known type, by which the modulated radio frequency is translated into signaling currents of the type originally impressed upon the radio transmitter at the transmitting station. See the receiving apparatus of United States patent to Affel, above referred to. The successive groups of 135 cycle current are accordingly detected by the apparatus R at the receiving station and impressed upon the circuit of an alternating current relay 22, the circuit of this

relay being tuned to 135 cycles. Each time a group of 135 cycle oscillations is received the relay 22 operates to maintain the relay 23 energized during the continuance of the group. Relay 23 will accordingly receive pulses corresponding to those transmitted by the dial D and will transmit these pulses over the circuit 24 to the selecting apparatus conventionally indicated at 25. If the code signal transmitted corresponds to that assigned to the particular receiving station illustrated, the selector apparatus is so actuated as to complete a circuit for the bell or other signaling device 26.

The details of the selector circuit are as shown in Fig. 2. The selector switch proper consists of three banks of contacts, A, B and C, over which wipers may be advanced step by step under the control of a stepping magnet S. Each bank of contacts consists of two groups of 11 contacts each, one of which corresponds to a normal position of the switch and is designated N, and of which the other contacts are numbered in regular order, beginning with 1 and ending with 0. The two groups of 11 contacts each are exactly alike and the individual contacts of each group are similarly connected to controlled circuits so that each group of 11 contacts constitutes, in effect, a complete switching unit. Each bank of contacts has two wipers associated therewith, one of which will normally rest upon one of the N contacts of the bank. The switches are so arranged that they can be advanced step by step in one direction only, and as one of the wipers passes over the successive contacts of the first group until it comes upon the N contact of the next group it has completed one cycle of operations. As it is then advanced step by step to the last N contact, it completes a second cycle of operations. At this time the second wiper rests upon the first N contact and as the switch is further advanced step by step until the second wiper reaches the second N contact it has completed a third cycle, and, similarly, as it is advanced step by step to the last N contact it completes a fourth cycle. Consequently, by means of two groups of contacts and two wipers for each bank each switch may be made to pass through four similar cycles by continuous step by step rotation, and each cycle will, to all intents and purposes, correspond to one complete operation of a single switch having 11 contacts arranged in one complete circular bank. Wherever, in the following description and in the appended claims, reference is made to the normal position of the switch it will be understood that by this is meant any setting of the switch whereby either one of the wipers rests on any one of the normal contacts designated N. The wipers on banks A and B are such as not

to bridge the contacts between successive steps as shown in Fig. 2^a, while the wipers on bank C are such as to make contact with the following point before breaking the contact on that point as shown in Fig. 2^b.

Of the three banks of contacts, the contacts of the bank B are arranged so that in response to a proper received code combination successive translating circuits are operated whereby the signal 26 is finally actuated. In the case of the circuit illustrated, the selector apparatus is arranged to properly respond to dialing of the number 1637. Of these digits, the first digit serves merely to restore all of the apparatus of the various selectors at the several stations to normal, and the last three digits constitute the actual selecting code for causing the actuation of the signal 26 at the desired station. Therefore, in the circuit illustrated, contacts numbered 3, 6 and 7 only are live contacts.

The contacts of banks A and C are so wired as to advance the selector switch to normal after having been advanced from a normal position in response to a dialing operation. All of the odd numbered contacts of the bank A except those contacts corresponding to the digits of the code number of the particular station involved are wired to a relay 2, while all of the even numbered contacts except those involved in the digits of the code number of the particular station are wired to the relay 3. Consequently, if the switch at any station is advanced to a position corresponding to a digit not involved in the code number of the particular station, one of the relays 2 or 3 will be released to control a self-interrupting circuit for the stepping magnet S, so that the switch will be advanced to the next succeeding normal contact. The automatically interrupting circuit of the magnet S is also controlled by the contacts of the bank C and the N contacts of the bank C are so wired as to interrupt the automatic stepping operation so that the switch is brought to rest on a normal contact. In the case of the switch at a station whose number is being dialed, each time the switch is successively advanced to a contact corresponding to one of the digits of its code number, a translating operation is performed and a selecting circuit completed. The further advance of the switch to the succeeding normal contact is then made under the control of the contacts of the bank C and the selected translating circuit, while the contacts of the bank A perform no function in advancing the switch to normal.

Further details of the apparatus may now be understood from a description of the operation, which is as follows: Let us assume that the dial D of Fig. 1 is actuated to transmit the number 1637. Successive groups of code impulses will be transmitted to the

relay 21 so that for each impulse of a group a series of 135 cycle oscillations are impressed upon the radio transmitter. These oscillations are translated into oscillations of 5 carrier frequency and radiated by the antenna TA. The radiated oscillations are then received by the antenna RA and impressed upon the radio receiver R, which operates to detect groups of 135 cycle oscillations 10 responding to the code impulses transmitted. Each group of 135 cycle oscillations actuates the relay 22 to transmit one pulse through the relay 23. As successive groups of pulses 15 are received, relay 23 transmits the pulses to the relay 1. Upon receiving the single pulse corresponding to the digit 1, relay 1 closes a circuit of the stepping magnet S and advances the selector switch from its normal position to its first contact. This 20 connects ground to one terminal of the slow release relay 2, thereby short-circuiting its winding. After a brief interval, the slow release relay 2 is deenergized. In this connection it should be noted that the relays 2 25 and 3 are made slow releasing so that when the wiper of the switch momentarily passes over one of the contacts connecting ground to the winding of one of its relays in being advanced to a further contact, the corresponding relay will not be released, but when the wiper is permitted to rest on such a contact for a short interval of time the relay will be deenergized to advance the switch to the next normal position in the 30 manner about to be described.

The release of the relay 2 completes the circuit of relay 7, which upon being energized opens, at its lower contact, the circuit of any of the selecting relays 11, 14 or 17, 40 which may have been previously energized and locked up. This restores the selecting circuits to normal and this operation occurs at all of the selectors of all of the stations so that each of the selectors is now ready to receive the next three digits of the code 45 number transmitted. Relay 7, at its upper front contact, completes a circuit for the relay 8, which is locked up over the upper back contact of relay 9. Relay 8, at its lower front contact, completes a self-interrupting circuit for the stepping magnet S, from battery, through the winding of said magnet, and over its interrupting armature, thence over the contact of relay 8 and over 50 the first contact of switch bank C to ground. This self-interrupting circuit is held closed over the successive contacts of the bank C until the succeeding normal contact N is reached. The wipers on bank C are such as 55 to bridge the contacts between successive points so as not to cause any interruptions when passing from one contact to another. The stepping circuit is now interrupted at contact N so that the switch comes to rest 60 and a circuit is completed from ground, over

the N contact, and through the winding of the relay 9. Relay 9, upon being energized, opens the locking circuit of the relay 8, which is at once released, the stepping circuit being now held open at the lower contact of the relay 8. All of the switches at 70 all of the stations now have one of their wipers resting on one of their normal contacts.

Upon receiving the six pulses corresponding to digit 6, the stepping relay S advances the switch six steps so that the wipers rest upon the contacts numbered 6. In the case of the circuit illustrated in Fig. 2, ground will now be connected over the sixth contact 80 of the bank B and over the upper back contact of relay 12 to one terminal of the winding of the slow-release relay 4, thereby short-circuiting said relay. After a brief interval, relay 4 is released and closes the circuit of relay 10. Relay 10, at its lower front contact, operates the selecting relay 11 which locks up over its lower contact. At its upper front contact, relay 10 completes a circuit, from ground, over the upper front contact of 85 relay 11, upper front contact of relay 10, and through the winding of relay 8 to battery. Relay 8 is accordingly energized and locked up as before. At its lower front contact, relay 8 completes a self-interrupting circuit over one of the wipers of the bank C so that the stepping magnet S advances the switch to the next normal position N. The self-interrupting circuit is 90 now open so that the switch comes to rest and the relay 9 is energized to unlock relay 8 as before. As soon as the wiper of bank B leaves the sixth contact, the short circuit is removed from relay 4, so that said relay 95 is again energized and opens the circuit of relay 10. A circuit is then completed for relay 12, from ground, over the upper front contact of locked up relay 11, over the upper back contact of relay 10, through the winding of relay 12 to battery.

All of the selectors at stations whose second digit is 6 will be operated in a manner similar to that above described. In the case of the selectors at stations none of whose digits are 6, however, the sixth contact of the A bank will be wired to a relay corresponding to relay 3, so that said relay will be short-circuited and will release its armature to complete the circuit of a relay corresponding to relay 7. In the case of stations whose third or fourth digit is 6, the sixth contact of B bank will be connected to a relay corresponding to relay 2 of Fig. 2 through the upper back contact of relay 15 and the lower back contact of relay 12, or through the lower back contact of relay 15, so that relay 2 will be short-circuited, and will release its armature to complete the circuit of a relay corresponding to relay 7. This relay in turn completes a circuit of a 120 125 130

relay corresponding to relay 8 so that the switches at those stations are automatically advanced step by step until their wipers rest upon the succeeding normal contact. The automatic stepping circuit at each of such selectors will be interrupted and a relay corresponding to 9 will be energized to unlock the relay corresponding to 8. All of the selector switches of the system are now 16 in normal position ready to receive the succeeding digit, which in the case assumed is 3.

Upon receiving the three impulses corresponding to the third digit 3, the stepping magnet S advances the selector switch three 17 steps, thereby connecting ground over one of the wipers of the B bank and the third contact thereof, and over the upper back contact of relay 15 and lower front contact of relay 12 to a terminal of the slow-release relay 5. 20 The winding of relay 5 is accordingly short-circuited and upon releasing its armature completes a circuit of relay 13. Relay 13, at its lower front contact, completes a circuit of relay 14, which is at once locked up. 25 At its upper front contact, relay 14 completes a circuit from ground, over the upper front contact of relay 13 and through the winding of relay 8 to battery. Relay 8 operates as before to advance the selector switch 30 to the succeeding normal position where it will come to rest. As soon as the wiper of the bank B leaves the third contact, the short circuit is removed from relay 5, so that said relay is again energized and opens the circuit of relay 13. A circuit is then completed for the relay 15, from ground, over the upper front contact of locked up relay 14, over the upper back contact of relay 13, through the winding of relay 15 to battery. 35

40 The operation above described takes place at all stations, the first three digits of whose numbers are 163. At stations none of whose digits is 3, a relay corresponding to relay 2 will be short-circuited by the third contact 45 of the A bank connecting to ground over one of the wipers of said bank. In the case of selectors, whose third digit is 3 but whose second digit is not 6, or whose fourth digit is 3, the third contact of B bank will be connected to a relay corresponding to relay 2 of Fig. 2 through the upper back contact of relay 15 and the lower back contact of relay 12, or through the lower back contact of relay 15, so that relay 2 will be short-circuited. 50 Relay 2, on being short-circuited releases and energizes a relay corresponding to 7, which in turn energizes and locks up a relay corresponding to 8, so that the selector switches at such stations are advanced to the next normal position. Relay 7 also removes battery from relay 14, causing it to release if locked up. At stations whose second digit is 3, relay 4 will release, operating relay 10, and locking up relay 11, and causing the selector to advance to the next 60

normal position N, as previously described.

When the set of impulses corresponding to digit 7 is received, the stepping magnet S advances the selector switch to its seventh contact, so that ground is connected over the 70 wiper and seventh contact of the bank B, over the lower front contact of relay 15 to the terminal of slow-release relay 6. Slow-release relay 6 is thus short-circuited and upon releasing completes a circuit for relay 75 16. Relay 16 in turn energizes and locks up relay 17. Relay 17 completes a circuit from ground, over its upper front contact, and over the upper front contact of relay 16, through the winding of relay 8 to battery. 80 Relay 8 is locked up and advances the switch to its next normal position, as already described. As the switch is advanced, the wiper leaves the seventh contact of the bank B so that the short circuit is removed from 85 the winding of relay 6. Relay 6, upon being energized, opens the circuit of relay 16, thereby releasing said relay and completing a signaling circuit as follows: From ground, over the upper front contact of relay 17, 90 upper back contact of relay 16, and through the signal 26 to battery. A parallel circuit is also established through the winding of the slow-operating relay 18 so that after a given time the relay 18 will open the locking circuit of relays 11, 14 and 17, thus 95 restoring these relays to normal. The release of relay 17 opens the circuit just traced for the signal 26 so that the signal now ceases. If desired, the operation of the signal may be stopped at any time by merely opening the contact of the key K. 100

Stations, the first three digits of whose code is 163, but having other numbers than 7 for their last digit will have their selectors advanced to the seventh point but at such stations a relay corresponding to relay 2 of Fig. 2 will be connected either to contact 7 on the A bank, or through lead 30 and the lower back contact of relays 12 105 or 15 to contact 7 on B bank and will therefore be short-circuited, so that the selectors at such stations will be restored to normal. 110

The selectors at other stations having 7 for one of their selective digits other than 115 the first will have their selectors advanced to the seventh contact. Except in the case of stations whose second selective digit is 3, and whose first selected digit is a number other than 6, the relays corresponding to 12 120 and 15 of Fig. 2 at such stations will not be energized. Consequently, a circuit will be completed from ground, over the seventh contact of the B bank at such stations, and over the lower back contact of the relay corresponding to 15, or the upper back contact of relay 15 and the lower back contact of relay 12 at such stations, and thence over conductor 30 to a terminal of the winding 125 of the relay corresponding to 2, which will 130

be short-circuited to restore the selector switch to normal in a manner already described.

Stations whose first selective digit is 7 will also have their selectors advanced to the seventh position by dialing the digit 7 of the station described. This will complete a circuit from ground, over the seventh contact of the B bank of the selectors at such stations, and over the upper back contact of the relay corresponding to relay 12 of Fig. 2 at such stations, thereby short-circuiting a relay corresponding to 4 at such stations. This will result in locking up the relays corresponding to 11 and 12 at such stations and also will result in the energization of the relay corresponding to 8, which restores the selector switches at these stations to normal. Relays corresponding to 11 and 12 will be unlocked and restored to normal under the control of the relay corresponding to 2, when the digit 1 is dialed in transmitting the next code number.

Stations whose second selective digit is 7, and whose first selective digit is 3 will likewise have their selectors advanced to the seventh point in response to the dialing of the last selective digit of the code number of the station called. At such stations a circuit will be completed from ground, over their seventh contacts, and thence over the upper back contact of a relay corresponding to 15 and the lower front contact of a relay corresponding to 12 to a relay corresponding to 5. This results in a sequence of relay operations which results in relays 14 and 15 being locked up and the selector being returned to its normal position as previously described. The relays 11, 12, 14 and 15 which are locked up will be released in response to the dialing of the digit 1 preceding the next code number.

The above illustrations are sufficient to indicate that when any selector at any station is moved off normal, it will be advanced to its next normal position in a manner similar to one of the ways already described, and while some of the selecting relays may remain locked up at stations which are not called, the dialing of the digit 1 preceding the next selective code will restore any relays locked up so that all the apparatus at all of the stations will be in normal condition before the first selective digit of any code combination of three selective digits is dialed.

It will be obvious that the general principles herein disclosed may be embodied in many other organizations widely different from those illustrated without departing from the spirit and scope of the appended claims.

What is claimed is:

1. In a signaling system, means for selectively signaling a desired station comprising

ing means for transmitting the code number of the station in the form of successive digits, means at a receiving station for receiving the code number, a selector switch at the receiving station controlled by said means, means to advance said selector switch off normal in response to each digit, means to bring said selector to normal between digits, a signaling circuit, and means actuated to complete said circuit by successively advancing the selector switch in response only to each digit of the code of that station.

2. In a signaling system, means for selectively signaling a desired station comprising 80 means for transmitting the code number of the station in the form of successive digits, means at a receiving station for receiving the code number, a selector switch at the receiving station controlled by said means, means to advance said selector switch off normal in response to each digit, means to bring said selector to normal between digits, 85 selecting relays, one corresponding to each selecting digit of the code number, means to successively operate the selecting relays in response to the successive operation of the selector switch, and a signaling circuit completed only upon the successive operation of said relays in response to the code for the 90 selected station.

3. In a signaling system, means for selectively signaling a desired station comprising means for transmitting the code number of the station in the form of successive digits, means at a receiving station for receiving the code number, a selector switch at the receiving station controlled by said means, means to advance said selector switch off normal in response to each digit, means to bring said selector to normal between digits, 100 selecting relays, one corresponding to each selective digit of the code number, means whereby the operation of the selector switch in response to the first selective digit will actuate one of said relays only if said digit is the first selective digit of the code number of that station, means whereby the successive actuation of the selector switch in response to additional digits will actuate the remaining selecting relays only when the digits receive correspond to the digits of the number of the station, and a signaling circuit controlled by said selecting relays. 110 115

4. In a signaling system, a transmitting station and a plurality of receiving stations, means at the transmitting station for selectively signaling a desired receiving station comprising means for transmitting the code number of the station in the form of successive digits, means at the receiving stations for receiving the code number, a selector switch at each receiving station controlled by said means, means to advance said selector off normal in response to each digit, 120 125 130

means to bring said selector switch to normal between digits, a plurality of selecting relays at each receiving station, one corresponding to each selective digit of a code number, means responsive to the first digit to bring the selector switches at all receiving stations and their associated apparatus to normal, means responsive to the second digit to actuate the selector switch at each receiving station and complete the circuit of the selecting relay thereat only if the digit corresponds to a digit of the code number of the station, means to actuate the other selecting relays at each receiving station in response to the successive actuation of the selector switch at each station only when the selective digits actuating the switch correspond to the remaining digits of the code number of the particular station, and means to complete a signaling circuit under the control of said selecting relays at the desired station.

5. In a radio telephone system, means for selectively signaling a desired station comprising means for transmitting the code number of the station in the form of successive digits, a radio transmitter, means to apply ringing current to said radio transmitter in accordance with the dialed code, means at a receiving station to translate received radio waves into ringing currents, means for translating the ringing currents into the code number, a selector switch at the receiving station controlled by said means, means to advance said selector switch off normal in response to each digit, means to bring said selector switch to normal between digits, a signaling circuit, and means actuated to complete said circuit by successively advancing the selector switch in response only to each digit of the code of that station.

6. In a radio telephone system, means for selectively signaling a desired station comprising means for transmitting the code number of the station in the form of successive digits, a radio transmitter, means to apply ringing current to said radio transmitter in accordance with the dialed code, means at a receiving station to translate received radio waves into ringing currents, means for translating the ringing currents into the code number, a selector switch at the receiving station controlled by said means, means to advance said selector switch off normal in response to each digit, means to bring said selector switch to normal between digits, selecting relays, one corresponding to each selective digit of the code number, means to successively operate the selecting relays in response to the successive operation of the selector switch, and a signaling circuit completed only upon the successive operation of said relays in response to the code for the selected station.

7. In a radio telephone system, means for selectively signaling a desired station comprising means for transmitting the code number of the station in the form of successive digits, a radio transmitter, means to apply ringing current to said radio transmitter in accordance with the dialed code, means at a receiving station to translate received radio waves into ringing currents, means for translating the ringing currents into the code number, a selector switch at the receiving station controlled by said means, means to advance said selector switch off normal in response to each digit, means to bring said selector switch to normal between digits, selecting relays, one corresponding to each selective digit of the code number, means whereby the operation of the selector switch in response to the first selective digit will actuate one of said relays only if said digit is the first selective digit of the code number of that station, means whereby the successive actuation of the selector switch in response to additional digits will actuate the remaining selecting relays only when the digits received correspond to the digits of the number of the station, and a signaling circuit controlled by said selecting relays.

8. In a radio telephone system, means for selectively signaling a desired station comprising means for transmitting the code number of the station in the form of successive digits, a radio transmitter, means to apply ringing current to said transmitter in accordance with the dialed code, means at a plurality of receiving stations to translate received radio waves into ringing currents, means at said stations for translating the ringing currents into the code number, a selector switch at each receiving station controlled by said means, means to advance said selector switch off normal in response to each digit, means to bring said selector switch to normal between digits, a plurality of selecting relays at each receiving station, one corresponding to each selective digit of a code number, means responsive to the first digit to bring the selector switches at all receiving stations and their associated apparatus to normal, means responsive to the second digit to actuate the selector switch at each receiving station and complete the circuit of the selective relay thereat only if the digit corresponds to a digit of the code number of the station, means to actuate the other selecting relays at each receiving station in response to the successive actuation of the selector switch of each station only when the selective digits actuating the switch correspond to the remaining digits of the code number of the particular station, and means to complete a signaling circuit under the control of said selecting relays at the desired station.

9. In a signaling system, means for selec-

- tively signaling a desired station comprising means for transmitting the code number of the station in the form of successive digits, means at the receiving station for receiving the code number, a selector switch at the receiving station controlled by said means, said switch being arranged to be operated in one direction only so that when advanced from its normal position it may thereafter be brought to normal by being further advanced, means to advance said selector switch off normal in response to each digit, means to further advance said selector switch to normal between digits, a signaling circuit, and means actuated to complete said circuit by successively advancing the selector switch in response only to each digit of the code of that station.
10. In a signaling system, means for selectively signaling a desired station comprising means for transmitting the code number of the station in the form of successive digits, means at a receiving station for receiving the code number, a selector switch at the receiving station controlled by said means, said switch being arranged to be operated in one direction only so that when advanced from its normal position it may thereafter be brought to normal by being further advanced, means to advance said selector switch off normal in response to each digit, means to further advance said selector switch to normal between digits, selecting relays, one corresponding to each selective digit of the code number, means to successively operate the selecting relays in response to the successive operation of the selector switch, and a signaling circuit completed only upon the successive operation of said relays in response to the code for the selected station.
11. In a signaling system, means for selectively signaling a desired station comprising means for transmitting the code number of the station in the form of successive digits, means at a receiving station for receiving the code number, a selector switch at the receiving station controlled by said means, said switch being arranged to be operated in one direction only so that when advanced from its normal position it may thereafter be brought to normal by being further advanced, means to advance said selector switch off normal in response to each digit, means to further advance said selector switch to normal between digits, one corresponding to the selective digit of the code number, means whereby the operation of the selector switch in response to the first selective digit will actuate one of said relays only if said digit is the first selective digit of the code number of that station, means whereby the successive actuation of the selector switch in response to additional digits will actuate the remaining relays only when the digits received correspond to the digits of the code number of the station, and a signaling circuit controlled by said selecting relays.
12. In a signaling system, a transmitting station and a plurality of receiving stations, means at said transmitting station for selectively signaling a desired receiving station, said means comprising means for transmitting the code number of the station in the form of successive digits, means at the receiving stations for receiving the code number, a selector switch at each receiving station controlled by said means, said switch being arranged to be operated in one direction only so that when advanced from its normal position it may thereafter be brought to normal by being further advanced, means to advance said selector switch off normal in response to each digit, means to further advance said selector switch to normal between digits, a plurality of selecting relays at each receiving station, one corresponding to each selective digit of a code number, means responsive to the first digit to bring the selector switches at all the receiving stations and their associated apparatus to normal, means responsive to the second digit to actuate the selector switch at each receiving station and complete the circuit of the selecting relay thereat only if the digit corresponds to a digit of the code number of the station, means to actuate the other selecting relays at each receiving station in response to the successive actuation of the selector switch of each station only when the selective digits actuating the switch correspond to the remaining digits of the code number of the particular station, and means to complete the signaling circuit under the control of said selecting relays at the desired station.
- In testimony whereof I have signed my name to this specification this 17th day of May, 1924.
- MILTON L. ALMQUIST.
